B. BENEDICT.
CIRCUIT CONTROLLER FOR FLASH LIGHTS.
APPLICATION FILED OCT. 23, 1917.

1,406,964.

Patented Feb. 21, 1922.

UNITED STATES PATENT OFFICE.

BERNARD BENEDICT, OF NEW YORK, N. Y., ASSIGNOR TO NATIONAL CARBON COMPANY, INC., OF NEW YORK, N. Y., A CORPORATION OF NEW YORK.

CIRCUIT CONTROLLER FOR FLASH LIGHTS.

1,406,964.

Specification of Letters Patent. Patented Feb. 21, 1922.

Application filed October 23, 1917. Serial No. 198,096.

To all whom it may concern:

Be it known that I, BERNARD BENEDICT, a citizen of the United States, residing at New York city, in the county of Bronx, 5 State of New York, have invented certain new and useful Improvements in Circuit Controllers for Flash Lights, of which the following is a specification, reference being had therein to the accompanying drawings, 10 forming part thereof.

My invention relates to circuit controllers for portable electric lights or flashlights, and relates more particularly to that kind of circuit controller in which a spring-pressed 15 manually operable push button is combined with a manually operable slide, for convenience in obtaining short or long periods of illumination as desired. Examples of this kind of circuit controller are found 20 in the patents to Conrad Hubert for portable electric lights, No. 1,047,525 of December 17, 1912, and No. 1,220,634 of March 27, 1917. Objects of my invention are to secure in circuit controllers of this kind, a 25 more effective circuit-controlling action, to render slight inaccuracies of construction negligible, to minimize the effects of wear, simplicity of construction, inexpensiveness of manufacture, durability, continued main- 30 tenance in operable condition, and other objects and advantages which will hereinafter appear.

My invention includes a movable circuit-controlling member at the inside of the casing part and co-operative with the push button for operating the latter, this inwardly located circuit-controlling member being operated by a manually operable member at the outside of the casing part. 35 More particularly, my invention includes a sheet metal slidable circuit-controlling member at the inner side of the casing part and which has a bifurcated end for engaging the push button for operating and guiding the latter, this slidable circuit-controlling 40 member being operated by means of a manually operable slide at the outside of the casing part and connected through the casing part to such slidable member. My in- 45 vention also includes features of construction and combinations of parts, as will appear from the following description.

I shall now describe the portable electric light or flashlight embodying the circuit controller of my invention illustrated in the

accompanying drawings and shall thereafter point out the invention in claims.

Figure 1 is a central longitudinal section with parts in elevation of a tubular portable electric light embodying my invention with 60 the circuit in the open condition.

Figure 2 is an elevation of an electrically conductive and insulated sheet metal reflector support which is included in the lamp circuit in the portable electric light embodying my invention which is illustrated in the drawings.

Figure 3 is a partial plan view on an enlarged scale, and shows the contact box and its adjuncts, including the movable circuit-controlling part carried thereby, as viewed 70 from above in Figure 1.

Figure 4 is an enlarged view similar to Figure 1 with parts omitted, and is a longitudinal section on a plane indicated by the 75 lines 4-4 of Figure 3 as viewed from below.

Figure 5 is a partial transverse section on planes indicated by the offset line 5-5 of Figure 4 as viewed from the right. 80

Figure 6 is an inverted plan view of the contact box and the movable circuit-controlling parts carried thereby, and shown as in the open circuit position.

Figure 7 is a similar view with the contact spring and push button omitted. 85

Figure 8 is another similar view of the contact box alone, all of the movable circuit-controlling parts being omitted.

Figure 9 is a plan view of a slidable cir- 90 cuit-controlling member at the inside of the contact box and cooperating with the push button.

Figure 10 is a plan view similar to Figure 3, illustrating the parts in circuit-closing 95 position.

Figure 11 is a longitudinal section similar to Figure 4, on a plane indicated by the line 11-11 of Figure 10 as viewed from below. 100

A distinctive feature of my present invention is a slidable circuit-controlling member 1, which is co-operative with a usual spring-pressed push button 2 and manually operable slide 3, carried by a suitable casing 105 part, shown as a metallic contact box or housing 4, which may be of substantially usual or of any suitable construction. The rounded push button 2 projects to the outside of the contact box 4 through a round 110

hole 5 therein, so that the push button 2 may be directly manually operated by pressure thereupon. The slide 3 is of sheet metal of a usual construction and is provided at its side with a pair of lugs 6 which extend to the inside of the contact box 4 through guide slots 7, and are shown as turned over inwardly toward each other upon the inner side of the flat slidable circuit-controlling member 1, which lies against the flat inner side of the contact box 4, and which is shown as provided adjacent to its rear end with lateral notches 8 of the correct width for snugly receiving the lugs 6 of the slide 3, so that the slidable circuit-controlling member 1 is secured in place at the inside of the contact box 4 and connected to the manually operable slide 3 to move therewith, the lugs 6 securing also the slide 3 in place upon the contact box 4. At its forward end the slidable circuit-controlling member 1 is of bifurcated construction, having therein a deep middle notch 9 providing forwardly extending lateral prongs 10. The notch 9 in the forward end of the member 1 is of narrower width than the diameter of the base of the push button 2, as clearly appears in the drawings, and in the retracted or open circuit position of this slidable circuit-controlling member 1 the ends of the prongs 10, which are shown as rounded, are located at the rear of and just out of contact with the base of the rounded push button 2, as clearly appears in the drawings, particularly in Figure 6 thereof.

The outwardly projecting push button 2 is located at the forward end of and is shown as formed in one piece with a spring metal strip 11, which at its rear end is firmly secured to the inside of the contact box 4, and is shown as riveted thereto by means of an inwardly projecting tubular stud 12 struck down or punched inwardly from the sheet metal material of the contact box 4. Near its rear end and just forward of the securing stud 12, the spring metal strip 11 is offset inwardly at 13, so as to provide, as appears in the drawings, a free space between the spring 11 and the adjacent inner surface of the top of the contact box 4, for the accommodation of the slidable circuit-controlling member 1 and the inner turned-over ends of the lugs 6 of the slide 3. Adjacent to the push button 2 and at a middle point 55 transversely, the spring metal strip 11 is shown as provided with an inwardly and rearwardly projecting spring contact prong or tongue 14, which is shown as formed in one piece with and as punched out from the spring metal strip 11.

The sheet metal contact box or housing 4 is firmly held in place upon the outside of a cylindrical battery-containing casing tube 15 of suitable insulating material such as vul- 65 canized fiber, by means of tubular rivets or

eyelets 16 and 17. The rivet 17 at the right side of the contact box 4, looking toward the front end of the device and as viewed from the right in the several figures of the drawings, at the inside of the insulating casing 70 tube 15 holds in place and electrically connects the contact box 4 with the forward end of a thin metallic circuit-completing strip 18, which is located in the rear end of the nonconducting casing tube 15, and extends from 75 the rivet-forming eyelet 17 to the rear end of the casing tube 15, where it is held in place by and is in electrical continuity with a usual screw-threaded metallic end band 19, which is shown as firmly secured in a usual 80 way on the rear end of the nonconducting casing tube 15, by means of eyelets 20, one of which appears in Figure 1. A usual metallic end cap 21 is screwed over the rear end band 19 and at the inside carries a usual battery-supporting coiled thrust spring 22, which forms an electrical connection with the zinc terminal 23 of a usual dry battery having a usual outer paper insulating tube 24.

A second similar circuit-completing metal strip 25 is located within the forward end of the nonconducting casing tube 15, and at its rear end is secured in place by an eyelet 26, the outer end of which is exposed within 95 the contact box 4 and underlies the contact-making free end of the contact prong or tongue 14 of the contact spring 11, in position to be engaged by and to form an electrical connection with this contact-making 100 prong or tongue 14, when the push button 2 is depressed to the contact-making or circuit closing position, as clearly appears in Figures 10 and 11 of the drawings. The circuit-completing metal strip 25 is shown as 105 extending forward flush with the end of the nonconducting casing tube 15, and at its forward end is shown as forming an electrical connection with a usual form of metallic reflector 27. The metallic reflector 27 is shown as 110 provided at its outer periphery with a slight out-turned flange 28, which is adapted to rest upon the inner part of the end surface of the nonconducting casing tube 15, which is shown as of considerable thickness. 115 The reflector 27 carries centrally thereof an inwardly projecting screw-threaded metallic lamp socket 29 of usual form and shown as formed in the same piece with the metallic reflector 27.

The reflector 27 and lamp socket 29 carried thereby are firmly supported within the outer end of the nonconducting casing tube 15, by means of a transversely arranged sheet metal supporting member 30, having 125 at its center a single screw-thread 31 which is engaged by the outside of the inwardly and outwardly screw-threaded lamp socket 29, which screws into the supporting member 30. The transverse supporting member 130

30 has a plurality, shown as three in number, of supporting sides or arms 32, which are firmly secured at the inside of the non-conducting casing tube 15, by means of tubular rivets or eyelets 33, the outer ends or heads of which are countersunk below the outer surface of the casing tube 15, as appears in the drawings in Figure 1 at the top. The eyelet 33 appearing at the top in Figure 1 also passes through and holds in place the forward or outer end of the metallic circuit-completing strip 25, which is shown as interposed between the inner surface of the casing tube 15 and the adjacent side arm 32 of the transverse supporting member 30, it being noted in this construction that the circuit-completing strip 25 forms a good electrical connection with the transverse sheet metal supporting member 30. At the outer or forward end of the nonconducting casing tube 15, an end glass, shown as a usual lens 34, is held in place by means of a usual flanged lens-holding ring 35, shown as screwed over a usual screw-threaded end band 36, having a slight inturned end flange 37 and shown as firmly secured upon the end of the nonconducting casing tube 15 by means of rivets 38, one of which appears in the lower part of Figure 1. A usual miniature incandescent lamp having a bulb 39 has its terminal-forming base 40 screwed into the lamp socket 29, and has its inwardly exposed central terminal 41 in contact with the carbon terminal 42 of the battery.

It is to be noted that the peripheral flange 28 of the metallic reflector 27 is spaced inwardly out of contact with the adjacent in-turned flange 37 of the screw-threaded end band 36, and it is also to be noted in this connection, that by reason of the counter-sinking of the outer ends or heads of the eyelets 33, as well as also by the slight outward spacing of the rear unthreaded end part of the screw-threaded end band 36, there is no electrical connection between the outwardly exposed lens-holding ring 35, or the screw-threaded end band 36, and the metallic reflector 27, or the lamp socket 29 carried thereby, these inner metallic parts being effectively electrically insulated from the outer metallic parts of the casing. It should be further noted in this connection, that the above described construction, including the transverse metallic supporting member 30, forms the subject of my patent for flash light, issued December 18, 1917, No. 1,250,945.

It will now be evident that the electrical circuit of the battery through the lamp is continuous excepting as it may be broken between the outer end of the eyelet 26 and the movable contact tongue 14 of the spring 11, it being noted, as hereinbefore described, that the eyelet 26 is in electrical connection

through the forward circuit-completing strip 25, and other above described intermediary parts, with the lamp base 40, and that the movable tongue 14 of the spring 11 is similarly in electrical connection 70 through the rear circuit-completing metal strip 18 and other intermediary parts, with the zinc terminal 23 of the battery.

In the circuit controller of my invention when the slide 3 is operated to close the 75 circuit, the forward rounded ends of the lateral prongs 10 at the sides of the forward middle notch 9 of the slidable circuit-controlling member 1, will engage with the outwardly projecting rounded push button 2 at 80 the lateral marginal edges thereof, and by reason of the rounded outer surface of the push button 2, these forwardly projecting lateral prongs 10 of the flat sheet metal circuit-controlling member 1 will partly override the push button 2, and will exert a cam action which will force the push button 2 inward from its projecting position, appearing in Figures 1 to 6 inclusive, to the depressed circuit-closing position thereof, appearing in 90 Figures 10 and 11, in which the contact-making prong or tongue 14 of the spring 11 is brought into engagement or into firm contact with the outer end of the metallic eyelet 26, thereby to complete the circuit of the 95 battery through the lamp as hereinbefore described. When the circuit-controlling slide 3 is retracted from its forward position appearing in Figures 10 and 11 to its rear position appearing in the other figures 100 of the drawings, the movable circuit-controlling parts, comprising the push button 2, spring 11 and prong 14, will be automatically returned to the open circuit position, by reason of the resiliency of the spring 11, 105 as will be readily understood. It will be noted that the flat metallic slidable circuit-controlling member 1 is firmly secured to the circuit-controlling slide 3 to move therewith by reason of the engagement of the lugs 110 6 of the slide 3 in the notches 8 of the member 1. It is to be noted that the construction and the arrangement of the parts are such that the circuit-controlling slide 3 in its circuit-controlling movement, at its forward 115 end passes over the push button 2, but does not come into contact therewith, the circuit-closing movement of the push button 2 being entirely accomplished by the slidable member 1, which is adapted to depress the push button 2 in advance of the slide 3, as will be clear from the drawings, particularly Figure 11 thereof. Heretofore a slide similar to the slide 3 has been arranged to come into contact with and directly operate a push 120 button similar to the push button 2, whereas in my construction it will be noted that the function of the slide 3 is to operate the slidable circuit-controlling member 1, and that this inner slidable member 1 operates 130

the push button 2. The bifurcated shape of the forward end of the slidable circuit-controlling member 1 serves a plurality of purposes. One of the important functions is that the spaced prongs 10 of the member 1 form between them in the notch 9 a guide for the outwardly rounded push button 2, effectively preventing lateral displacement of the push button 2 in the contact box 4, such as has heretofore sometimes given trouble in prior constructions in which my invention was not embodied. Another advantage of this bifurcated construction of the slidable circuit-controlling member 1 is that the push button 2 will not be pushed in too far or to an excessive extent which might bend or otherwise damage or distort the movable parts of the circuit-controller, such for example as the spring 11 or its contact-making tongue 14. A further advantage is that there is no friction or rubbing of any metallic part upon the rounded outer end of the push button 2 such as would have a tendency to scratch and mar the finish of its polished surface. Also the spaced prongs 10 of the member 1, by reason of their engaging the sloping lateral edge parts of the push button 2, cause the member 1 to exert a more effective wedging or cam action on the push button 3. It will be noted that by reason of the fact that the slidable circuit-controlling member 1 lies flat against and is guided by the inner surface of the contact box 4, that its action upon the push button 2 to depress the latter will be very firm and effective, it being impossible for the slidable member 1 to yield, whereby a full extent of circuit-controlling movement will be imparted to the push button 2 and transmitted to the spring 11 and contact tongue 14 thereof.

It is obvious that various modifications may be made in the construction illustrated in the drawings and above particularly described within the principle and scope of my invention.

I claim:

1. A circuit controller for a portable electric light having, in combination, a metallic casing part, circuit-completing means including a spring metal strip at the inside of said casing part and fixed at one of its ends thereto and at its other end having a rounded push button projecting from the inside to the outside of said casing part and there adapted to be exposed for manual actuation, a slidable circuit-controlling member in contact with the inner side of said casing part and slidable into and out of engagement with the push button thereby to effect the closing or the opening of the circuit, said circuit-controlling member being bifurcated so as to engage with the marginal parts only of the push button, and a manually operable

slide at the outside of said casing part and connected to said slidable circuit-controlling member for operating the latter.

2. A circuit controller for a portable electric light having, in combination, a casing part, an automatically returning contact member at the inside of said casing part and including a rounded push button projecting to the outside of said casing part for manual actuation, a slidable circuit-controlling member at the inside of said casing part and having a bifurcated end slidable into or out of engagement with the push button thereby to effect the closing or the opening of the circuit, and a manually operable slide at the outside of said casing part connected to said slidable circuit-controlling member for operating the latter.

3. A circuit controller for a portable electric light having, in combination, a metallic casing part provided with guide slots for a manually operable slide, circuit-completing means including a spring metal strip at the inside of said casing part and fixed at one of its ends thereto and at its other end having a rounded push button projecting to the outside of said casing part for manual actuation, a flat sheet metal slidable circuit-controlling member at the inside of said casing part between said casing part and said spring metal strip and having a bifurcated end slidable into or out of engagement with the push button thereby to effect the closing or the opening of the circuit, and a manually operable slide at the outside of said casing part having projections passing through said guide slots in the casing part and engageable with said slidable circuit-controlling member for operating the latter.

4. The invention claimed in claim 3 in which said slidable circuit-controlling member is adapted in its circuit-closing movement to depress said push button in advance of said slide, whereby the slide may move over the depressed push button without touching the latter.

5. The invention claimed in claim 3 in which said metallic casing part forms a contact box containing said contact-making spring metal strip and slidable circuit-controlling member.

6. A circuit-controller for a portable electric light having, in combination, a metallic casing part provided with guide slots for a manually operable slide, an automatically returning contact member at the inside of said casing part and including a rounded push button projecting to the outside of said casing part for manual actuation, a slidable circuit-controlling member at the inside of said casing part and slidable in contact with the inner side of said casing part into or out of engagement with the outer rounded end of said push button thereby to effect the closing

- or the opening of the circuit, said circuit-controlling member being provided with lateral notches in its opposite edges, and a manually operable slide at the outside of said casing part having lugs passing through said guide slots in the casing part and fitting into said lateral notches in the circuit-controlling member, said lugs being turned over upon the inner side of said circuit-controlling member, whereby said manually operable slide is secured to said circuit-controlling member to operate the latter and both of these parts are secured upon said casing part.
- 15 7. A circuit-controller for a portable electric light having, in combination, a casing part, an automatically returning contact member at the inside of said casing part and including a push button projecting from the 20 inside to the outside of said casing part and there adapted to be exposed for manual actuation, a slidable circuit-controlling member at the inside of said casing part and there slidable into or out of engagement with the push button thereby to effect the closing 25 or the opening of the circuit, and a manually operable slide exposed at the outside of said casing part for manual actuation and connected to said slidable circuit-controlling member for operating the latter, said slid- 30 able circuit-controlling member being adapt- ed in its circuit-closing movement to depress said push button in advance of said slide, whereby the slide may move over the de- pressed push button without touching the 35 latter.

In testimony whereof, I have affixed my signature to this specification.

BERNARD BENEDICT.
